GLEN D. COLE AND KENNETH F. KLENCK, OF LIBBY, MONTANA.

DRUMHEAD-TENSIONING DEVICE.

Application filed January 18, 1923. Serial No. 613,494.

This invention relates to improvements in percussion drums, including a novel drum head tightening apparatus.

The primary object of this invention is the provision of an improved apparatus by means of which the drum head may be quickly and conveniently adjusted in a minimum of time, as to effectively position the drum head in a desired taut or slack position.

A further object of this invention is the provision of drum head tightening apparatus, by means of which the drum head may be most effectively tightened upon its drum shell, as to occasion no unnecessary or eccentric strain, so that the drum may produce a superior quality tone and withstand the ordinary strains placed thereon incident to adjustment and play.

A further object of this invention is the provision of a drum head tightening apparatus which may be universally used in connection with all types of percussion drums, such as snare drums, bass drums, kettle drums, combination organ drums, banjos, and the like, including a pitch adjusting means by which the drum head may be drawn to the desired taut or slack position, so that the drum may sound in different keys.

A further object of this invention is the provision of an improved drum head tightening apparatus, by means of which the hoop of the drum head may be evenly drawn about its entire circumference into taut relation, so that no warping of the hoop will take place.

A further object of this invention is the provision of drum head tightening apparatus of the above mentioned character, by means of which the player may instantly tighten or slacken the drum head so that there will be no occasion for neglect to loosen the drum head, as is frequently the case, resulting in rupture incident to extreme temperature changes.

Other objects and advantages of this invention will be apparent during the course of the following detailed description.

In the accompanying drawings, forming a part of this specification, and wherein

similar reference characters designate corresponding parts throughout the several views.

Figure 1 is a cross sectional view, taken through the improved drum substantially 55 along the line A—A of Figure 3, showing the novel details of the improved drum head tightening apparatus.

Figure 2 is a fragmentary view, partly in section, showing the novel devices which are 60 placed at a plurality of points about the drum and for connection to the drum heads to effect drum head adjustment.

Figure 3 is a cross sectional view, taken substantially on the line 3—3 of Figure 2. 65

Figure 4 is a cross sectional view, taken substantially on the line 4—4 of Figure 2.

Figure 5 is a perspective view of an operating handle used to effect drum head adjustment. 70

Figure 6 is a fragmentary perspective view of a ring gear used in connection with the improved drum head adjusting apparatus.

Figure 7 is a cross sectional view, taken 75 substantially on the line 7—7 of Figure 1, showing more particularly a pawl and ratchet mechanism to hold a desired drum head adjustment.

In the drawings, wherein for the purpose 80 of illustration is shown but the preferred embodiment of this invention, the letter A designates the ordinary drum details, which may include a shell 10, and drum head construction 11, while the letter B may designate the improved drum head adjusting apparatus, comprising an annular rack 12; means 13 for operating the annular rack 12; and devices 14 for operative connection to the annular rack and drum head for adjustment of the latter by operation of the annular rack. 85

Referring to the drum shell 10, the same may be of any approved construction, such as is used in connection with the various 90 types of percussion drums, and may include one or more of the drum head constructions 11. The drum head construction 11 may be of the well known type, consisting of the skin or vellum 20, having the circumferential portions thereof wrapped about and secured to the circular flesh hoop 22, and in- 100

cluding the tension hoop 23 adapted to receive portions of the adjusting apparatus B, and to engage the flesh hoop 22 for maintaining the drum head in proper relation 5 upon the shell 10.

Referring to the improved drum head adjusting apparatus B, the annular rack 12 is of novel construction, preferably being circular or segmental in cross section, and having teeth 25 provided on a side thereof, which are of a construction to conform to the general circular cross sectioning of the annular rack. This rack 12 is preferably mounted within the compartment of the shell 10, being supported at a plurality of points by bearings or hangers 27, which are attached in any approved manner to the interior surface of the drum shell 10, as to extend radially inwardly of said shell; said 10 bearings or hangers 27 having circular openings 28 therein, which are in relative circular alignment about the interior of the shell 10 to reciprocably receive the annular rack 12 therein for circumferential movement 15 concentrically of said shell.

Referring to the devices 14, a plurality of the same are provided circumferentially about the drum, at equi-distant points, for operation by movement of the annular rack 12, as will be subsequently described, to effect the transverse movement of the hoops 22 and 23 of the drum head construction 11, for adjustment of the skin or vellum 20 to the desired tightness or slackness. The devices 14 may be of identical construction, and each of the same includes a short shaft 30 rotatably carried by the shell 10, as to extend radially therethrough. In order to properly position the shaft 30 in stable manner, it is preferred that a circumferential groove 31 be provided thereabout within which a wear plate or supporting washer 32 may engage, at the exterior surface of the shell 10. Upon the interior surface of the shell 10, a metal bearing 33 is preferably provided, within which the shaft 30 is journalled; the bearings or members 32 and 33 preferably being secured together and to the shell 10, as by rivet or bolt elements 34, substantially as is illustrated in Figure 3 of the drawings. In this manner, an end of each shaft 30 extends interiorly of the shell 10 to receive a relatively small spur gear 35 in meshing engagement with the teeth 25 of the annular rack 12, while the other end of each shaft 30 extends exteriorly of the shell 10, and has a spur gear 37 keyed thereto.

Each of the devices 14 includes a rack bar 38 which extends transversely of the drum, substantially at right angles to the plane defined by the annular rack 12, and is provided with a plurality of teeth 39 in meshing relation with the teeth of the spur gear 37. This bar 38 is supported exteriorly of

the shell 10, by means of a bearing 40, so that the same may be transversely slid; it being preferred that the portion of the bar 38 upon which the teeth 39 are provided be flattened, while the outer portion of the bar 38 is circular in cross section to permit the easy sliding of the same through the bearing 40. The free end of each rack bar 38 is provided with a headed portion 42, adapted for detachable connection to segmental attaching members 44, which are carried by the hoop 23. The members 44 are preferably of metal and include an upstanding hollow segmental portion, providing a compartment 45 therein, and having their lower portions flanged, as at 46, for attachment by rivets or other elements 47 to the outer circumference of the drum hoop 23, substantially as is illustrated in the drawings. A flat wall 49 of the upstanding portion of each attaching member 44 is provided with a keyhole opening 50 therein adapted to receive the headed end 42 of a rack bar 38 in detachable manner, thus providing a joint construction, which will permit quick attachment or detachment of the drum head construction with respect to the drum.

The details above described may be provided upon any of the various types of drums. In the drawings, a single tension drum is shown, having two drum head constructions, which are substantially duplicates of each other. In this type of construction it is to be noted that each spur gear 37 may have a pair of rack bars 38 meshing therewith and extending to the oppositely disposed drum head constructions 11, so that said drum head constructions may be simultaneously adjusted upon movement of the spur gears 37. Housings 55 may be attached exteriorly upon the drum shell 10 to encase the toothed portions of the rack bars 38 and the pinions 37, so that only the free end portions of the rack bars extends in slidable manner transversely through said housings 55. This provides a neat protecting structure.

In the case of the kettle drum, only one rack bar 38 need be provided for each spur gear 37, as can well be understood by those skilled in the art to which this invention pertains. By using two of the annular racks and necessary attachments, a drum including two of the head constructions 11 can have said heads adjusted at different tensions, so that they may sound in different keys.

Referring to the means 13 for operating the annular rack 12, the same includes a shaft 60 altogether similar to the shafts 30 above described, and radially mounted through the shell 10 for rotation, in manner similar to the mounting of each of the shafts 30. This shaft 60 is provided with a pinion

61 at the inner end thereof in meshing relation with the teeth of the annular rack 12. At its outer end, and exteriorly of the shell 10, a polygonal head 62 may be provided, 5 which may be engaged in the polygonal socket opening 63 of a detachable operating handle or member 64, to effect rotation of the shaft 60 to circumferentially move the annular rack 12. A pawl and ratchet mechanism is provided to maintain the shaft 10 against movement, which includes a ratchet wheel 66, keyed or fastened in any approved manner to the shaft 60 intermediate the shell 10 and the pinion 65, and 15 which has a pawl element 67 which is oscillatively supported within the shell 10 and upon the same, having a spring 68 which normally maintains the same in engagement with the teeth of the ratchet wheel 62. A headed end 69 of the pawl 67 may extend outwardly through an arcuate slot 70, in the shell 10, for manual operation, so that the improved drum head adjusting means may be operated to slacken the taut position of 25 the drum head or heads.

From the foregoing description of this invention, it is apparent that a drum head tightening or adjusting apparatus has been provided, by means of which a player may 30 quickly tension or release the drum head construction and in the most effective manner. The set of spur gears 35 carried inwardly of the shell 10, by the rotatable shaft 30, are of course operated simultaneously 35 upon rotation of the annular rack 12. Likewise, the set of spur gears 37 exteriorly carried by the shaft 30 are operated simultaneously to effect simultaneous transverse movement of all of the rack bars 38 carried 40 by a drum construction, the direction of movement of the rack bars 38 preferably being at exactly right angles to the planes defined by the annular rack 12 and the drum head construction. This movement 45 for adjustment of the drum head will permit of the even tightening of the same in contradistinction to the diagonal tightening devices which have been used heretofore. When used on the type of percussion drum 50 embodying batter and snare drum heads, the improved tightening apparatus will in no way interfere with the strings of the snare heads. A further and important feature of the improved apparatus 55 is the means by which the drum heads may be individually quickly detached from the drum shell. When used on kettle drums, the player can tighten or loosen the drum head to give the required tone, the adjusting 60 operating necessary requiring only a second or so, if it is necessary to change the tone of a drum in the middle of a selection being played. It is at once evident that this permits the player to give his undivided attention to the playing of his various 65

drums, without the distraction of prolonged adjustment necessary upon many types of drums.

Various changes in the shape, size and arrangement of parts may be made to the form 70 of the improved drum head adjusting apparatus herein described, without departing from the spirit of the invention or the scope of the claims.

We claim:

1. A drum comprising a shell, a head on each side of said shell, an annular rack in said shell, means for adjusting the annular rack, said means being carried by the shell and operated externally thereof, and drum head adjusting means extending through the walls of the shell and operated by movement of said rack.

2. A drum comprising a shell, a drum head tightening device comprising an annular rack positioned within the shell, means for circumferential adjustment of the annular rack, said means being operated externally of the shell, a plurality of shafts journaled in the shell and extending radially thereof, a set of spur gears on the inner portions of said shafts meshing with said rack to impart rotation to the shafts upon movement of the rack, a second set of spur gears carried by the outer end portions of said shafts, and drum head engaging racks meshing with the second set of spur gears and adapted to be moved thereby transversely of the plane of the annular rack.

3. A drum construction comprising a shell, 100 a drum, an annular rack mounted interiorly of the shell for circumferential movement thereabout, and means carried by the shell and having a portion positioned within the shell and connected to the rack and a portion 105 positioned externally of the shell and engaging the drum head to effect adjustment of the drum head by movement of the rack.

4. A drum comprising a shell, a drum head, an annular rack movably carried interiorly of the shell for circumferential movement thereabout, means connected to the rack and extending exteriorly of the shell for connection to the drum head, and means 110 for adjusting the rack to move said first mentioned means to adjust said drum head.

5. A drum construction comprising a shell, a drum head, an annular rack mounted within the shell and circumferentially movable about the shell, a plurality of shafts rotatably carried by the shell and extending radially thru the walls thereof, a set of gears carried by said shafts in meshing relation with the rack, a second set of gears carried by the outer end portions of the shafts, 120 racks slidably carried by the shell externally thereof in meshing relation with the second set of gears, means connecting the last mentioned racks to the drum head, and means for moving said annular rack.

6. A drum construction comprising a cylindrical shaped shell, a drum head, an annular rack, means mounting said annular rack interiorly of the shell for concentric circumferential movement therein, a plurality of shafts radially carried by said shell for rotation having the ends thereof interiorly and exteriorly extending through said shell, a set of gears carried by the inner ends of said shafts in meshing relation with the annular rack, a set of gears exteriorly carried by said shafts, rack bars, housings carried by

the shell in covering relation to the outer gears and mounting said rack bars exteriorly of the shell for transverse sliding thereon ¹⁵ upon opposite side of and in meshing relation with the outer set of gears, means connecting said drum head to the rack bars, and means for selective positioning and movement of the annular rack, whereby said rack bars may be adjusted for tensioning of said drum head.

GLEN D. COLE.
